ATTORNEY

UNITED STATES PATENT OFFICE.

ANDREW LITTLE, OF NEW YORK, N. Y.

DESIGN FOR A FONT OF PRINTING-TYPE.

SPECIFICATION forming part of Design No. 13,700, dated March 6, 1883.

Application filed January 13, 1883. Term of patent 7 years.

To all whom it may concern:

Be it known that I, ANDREW LITTLE, of the city, county, and State of New York, have invented and produced a new and original Design for a Font of Printing-Type, of which the following is a specification.

The nature of my design is clearly shown in the accompanying typographic impression, to which reference is made; and it consists of an unshaded letter. In the A, C, D, H, L, N, O, Q, and U the letters are ornamented about centrally by the light inclined parallel lines, and the E and F are ornamented by the light parallel horizontal lines. In the C, D, E, F, G, L, P, R, S, T, U, Y, and 2 the curling termination followed by the light dot is found. The upper right-hand portion of the K terminates in the dot, as shown. In the M the right and left hand central portions of the letter form the triangular ornament at the base of the letter, and this triangular termination is found at the base of the V, and also at the upper

portion of the W. In the S the upper right-hand termination is followed by the curved termination crossing the letter and having the 25 dot termination. The T is crossed upon the right-hand by the light vertical line. In the symbol & and the dollar-mark the curved termination followed by the dot is found. In the figures 2, 3, 7, and 9 the curved termination 30 followed by the dot is found.

The character of the design is preserved in the lower-case and punctuation-marks, the g, j, k, and 2 terminating in the curved termination followed by the dot, and the w having the 35 central triangular ornament already described.

Having now set forth my invention, I claim—

The design for a font of printing-type, as shown and described.

ANDREW LITTLE.

In presence of—

WILLIAM V. H. HICKS,
A. SIDNEY DOANE.
